United States Patent Office

Des. 221,721
Patented Aug. 31, 1971

221,721

DISPLAY PANEL

James L. Hoskins, 230 Hunter, Haysville, Kans. 67060

Filed Apr. 20, 1970, Ser. No. 22,521

Term of patent 14 years

Int. Cl. D20—03

U.S. Cl. D96—12

FIG. 1

FIG. 2

FIG. 3

FIG. 4

FIG. 1 is a perspective front view of the display panel with a transparent center section, illustrating my new design;

FIG. 2 is a sectional view taken along line 2—2 of FIG. 1;

FIG. 3 is a sectional view taken along line 3—3 of FIG. 1; and

FIG. 4 is a back view of the panel.

I claim:

The ornamental design for a display panel, as shown and described.
